ELASTIC WORK HOLDER ATTACHMENT FOR
VISE JAWS

Herman P. Fest, Monrovia, Calif.

Application November 1, 1943, Serial No. 508,562

2 Claims. (Cl. 81—38)

This invention relates to work holder attachments for vise jaws and more particularly to an elastic work holding attachment such as rubber or the like.

Among the objects of the invention are: to provide an improved elastic attachment which, upon application to each jaw portion of the vise, will project the shape and finished surfaces of articles gripped by the vise; to provide in an attachment for vise jaws improved means adapted to snugly grip jaws of vises not conforming exactly to standard dimensions; to provide a work holder which, upon application, will yield in an improved manner to irregularities in the vise due both to variations in size as well as inaccuracy in workmanship; to provide improved means yieldably applicable to the jaws of a vise which will conform to the shape of articles gripped and which will possess a non-slip quality both in relation to the vise and to the work held thereby; to provide more specifically as an article of manufacture an improved work holder for vise jaws embodying elastic extruded material from which to cut to exact lengths for vise jaw attachments wherein such vise jaws embody variations in size, in combination with a bendable half hard spring metal strip for securing such attachments to vise jaws; and, to provide a vise jaw attachment gripping by virtue of its inherent resiliency, which is shock absorbing, reduces vibration in the work being operated upon and is adapted better to meet the requirements for which it is intended.

The present invention is a continuation in part of my copending application, Serial Number 417,715, filed November 3, 1941, which resulted in Patent #2,340,316, dated February 1, 1944.

Referring to the accompanying drawing wherein is shown the alternate embodiment of the invention set forth in the patent supra,

Fig. 1 is a perspective view of the article applied to the jaws of a vise.

Fig. 2 is a perspective view of the attachment per se shown applied in Fig. 1, but on a larger scale.

Fig. 3 is a section taken on line 3—3 of Fig. 2.

Fig. 4 is a perspective view per se of the yieldable gripping bar shown in Fig. 2 on a somewhat larger scale. The dotted indication in the former view illustrates the manner of turning the ends inwardly after the bar has been applied to the attachment.

Fig. 5 is a perspective view on a smaller scale of the extruded parent strip from which the at-

tachment shown in Fig. 2 is cut to the exact length needed.

Referring in detail to the drawing, the work holder as seen in Fig. 2 comprises an elastic arched top jaw facing wall 6 to overlie the top surface of a vise jaw 7 shown in Fig. 1, and an elastic jaw facing gripping wall 8 depending downwardly from that long edge of said arched top wall which is located nearest the gripping face of the illustrated jaw when said holder is applied. Said gripping wall is shown joined to said arched top wall at an acute angle, said acute angle being of a lesser degree than that embraced by the meeting walls of the vise jaw 7 which said arched and gripping walls overlie, the inherent resiliency of said top and gripping walls along their line of juncture when stressed during application of the holder to the jaw tending to inspring each of said walls into a snug vise gripping position.

Means is provided to maintain the applied gripping position of the holder, said means comprising providing an opening 9 extending longitudinally through said downwardly depending gripping wall in a downwardly spaced parallel relation to said arched top wall 6 and to each of the opposite faces 10 and 11 of said gripping wall 8, a half hard spring metal strip 12 (see Fig. 4) being projected through said opening and having the outer protruding ends thereof deflected toward the face of the vise which said gripping wall overlies to form wings 13 and 14 to grip the end walls of the vise jaw in a subjacent relation to said arched top wall, said wings normally assuming an angle of less than ninety degrees in relation to the intervening portion of the strip as dottedly indicated in Fig. 4.

The stock from which each elastic work holder is cut to the exact length to suit the particular jaw to which it is to be subsequently applied, consists of a parent strip of rubber 15 acutely angular in cross section as shown in Fig. 5.

In the manufacture of the article the rubber is extruded from a suitable die while in a plastic condition, the rectangular opening 9 being at the same time formed by the die during the extruding operation. Thereafter said parent strip is cut into the proper lengths preparatory to inserting and bending the metal strip 12 in the manner already stated.

In applying the work holder to the sides of each jaw of the vise 16, as operatively shown in Fig. 1, the fingers of the hands spring the yieldable wings 13 and 14 outwardly as shown in the direction in which the arrows point in Fig. 4, the

arched top wall is placed over the top wall of the vise at the same time flexing the downwardly depending wall outwardly along its line of juncture with the arched top wall until the acute angle of the holder is made to conform snugly to the acute angle of the vise whereupon the gripping wall is pressed home against the gripping face of the vise after which the wings are released to hold in place, in a glove like fashion, the elastic walls after being fitted to the vise.

It will be seen from the construction just described that, owing to the elasticity of the material in general, as well as at the juncture of the gripping wall 8 and arched wall 6, said arched top wall will also conform closely to considerable variations in the contour of the top surface of the vise.

The fact that the wings 13 and 14 normally assume an angle of less than ninety degrees in relation to the intervening portion of the strip makes possible the application of the holder to different vise jaws embodying variations in size and shape.

It will be observed further that, aside from the advantages last pointed out, owing to the elastic or adhesive glove-like application of the holder to the vise while articles being worked upon are gripped, that the articles will be less likely to slip together with the holder when the artisan's tools are being applied to the article, which would not result in the case of a metal to metal arrangement. Thus the shock absorbing quality, as well as the non-slip condition which is augmented by the elastic arched top wall, produces a device long sought for by the trade.

What is claimed is:

1. As an article of manufacture, a vise lining rubber member acutely L-shaped in cross section having a tunnel extending longitudinally through one of its limbs in an inwardly spaced relation to each face and the free edge of the limb which it occupies, and a spring metal strip bendable after insertion to form at each end thereof a vise gripping wing extending through said tunnel.

2. A jaw attachment for vise jaws comprising an elastic arched top wall to overlie the top surface of the vise jaw, an elastic gripping wall depending downwardly from that long edge of said top wall which is located nearest the gripping face of such jaw when said attachment is applied, said gripping wall joining said arched top wall at an acute angle, the inherent elasticity of said walls along the line of their juncture during application of the attachment to the vise jaw tending to inspring each of said walls to a vise gripping position, and means to maintain the applied gripping position of said walls, said means comprising a spring metal strip extending through a tunnel provided longitudinally through said downwardly depending wall in a spaced parallel relation to said arched top wall and the bottom edge of said depending wall and in an inwardly parallel spaced relation to each face of said gripping wall, said strip being transversely deflectable at the outer ends thereof toward the face of the jaw which said gripping wall overlies to form wings to grip the end walls of said vise jaw in a subjacent relation to said arched top wall, said wings normally assuming an angle of less than ninety degrees in relation to the portion of said strip intervening between them.
